UNITED STATES PATENT OFFICE.

HARRY C. GINGRICH, OF ROYERSFORD, PENNSYLVANIA.

UNION SUIT.

1,161,471.

Specification of Letters Patent.

Patented Nov. 23, 1915.

Application filed May 20, 1915. Serial No. 29,282.

To all whom it may concern:

Be it known that I, HARRY C. GINGRICH, a citizen of the United States, and a resident of Royersford, in the county of Montgomery and State of Pennsylvania, have invented certain new and useful Improvements in Union Suits, of which the following is a specification.

The principal object of the present invention is to provide a neat, attractive and comfortable union suit which requires comparatively little material in its manufacture and which, while permanently closed and free from crotch flaps, buttons, fastening devices and the like, is capable of fulfilling all the requirements which are usually met by such openings, flaps and like devices.

The invention will be claimed at the end hereof, but will be first described in connection with the accompanying drawings, in which—

Figure 1, is a front view, Fig. 2, is a rear view, and Fig. 3, is a diagrammatic view, drawn to an enlarged scale, and looking inward.

The union suit is a three piece garment and it consists of a tubular body 1, tapering or running toward a point at both the front and back from points 2 on opposite sides of the waist line inward to the crotch 3, and the back 4 and front 5 are sewed together at the crotch leaving leg openings from the waist to the crotch. The body is a seamless knitted tubular fabric and it may be said to be cut to a blunt point 3 along the lines 3—2. It is shown the same at the back as at the front and the two blunt points are seamed together at 3.

7 and 6 are seamless tubular legs sewed to the leg openings, as indicated at 8 and 9, 40 or otherwise expressed, the tube constituting each leg is cut across on a diagonal line at its top and the part so cut is sewed throughout its extent to the leg opening in the body. As shown the outside edge 10 of each leg 45 portion is longer than the inside edge 11 thereof, although this is not necessary in all cases. The lower part of the leg is cut irregularly to produce an attractive appearance and is shown as bordered with lace 12 50 as are also the neck and arm hole openings 13 and 14. It is evident that the crotch of the garment is closed and by making the leg, including the part 12 thereof, sufficiently large the crotch portion and one leg 55 of the garment can be pushed to one side when necessary.

What I claim is:

A closed crotch union suit consisting of a seamless tubular knitted body tapering at 60 both the front and back from opposite sides of the waist line inward to points, a seam connecting the knitted fabric of the points together and forming a closed crotch with a leg opening on each side thereof extending 65 to the waist line whereby elasticity and hip room are provided without initial stretch, and tubular knitted legs sewed to the knitted edges of said openings.

In testimony whereof I have hereunto 70 signed my name.

HARRY C. GINGRICH.
